Atty.

UNITED STATES PATENT OFFICE.

CONRAD B. MANSBACH, OF BROCKTON, MASSACHUSETTS, ASSIGNOR OF ONE-HALF TO
FRANK L. PRICE, OF BROCKTON, MASSACHUSETTS.

INNERSOLE.

1,155,687.

Specification of Letters Patent. Patented Dec. 28, 1915.

Application filed March 31, 1915. Serial No. 18,259.

To all whom it may concern:

Be it known that I, CONRAD B. MANSBACH, a citizen of the United States, and resident of Brockton, in the county of Plymouth and 5 State of Massachusetts, have invented certain new and useful Improvements in Innersoles, of which the following is a specification.

This invention relates to an inner sole 10 for welted shoes, composed of a body layer usually of leather and a facing layer usually of canvas cemented to one side of the body layer, and having a loop-like molded hollow rib or wale forming a lip to engage the inseam stitches, which unite the welt and upper to the inner sole.

One object of the invention is to laterally stiffen the said lip by corrugating one or both of its sides, so the lip is buttressed 20 against distortion or bending under lateral pressure against it.

Another object of the invention is to render the toe portions of the facing layer and lip impervious to hot vapor used for softening parts of a shoe upper associated with the inner sole, and thus prevent the softening of the toe portion of the lip during the period of application of vapor to the toe cap and other parts of the upper while said 30 parts are partly assembled before the operation of lasting.

To these ends the invention consists in the improvements which I will now proceed to describe and claim.

35 Of the accompanying drawings forming a part of this specification: Figure 1 represents a plan view of an inner sole embodying my invention; Fig. 2 represents a section on line 2—2 of Fig. 1; Fig. 3 represents a section on line 3—3 of Fig. 1; Fig. 4 represents a section on line 4—4 of Fig. 1; Fig. 5 represents a perspective view of a section cut from the inner sole along the lines x—x and 40 y—y of Fig. 1; Fig. 6 represents a fragmentary side view showing a different embodiment of the invention; Fig. 7 represents a section on line 7—7 of Fig. 6; Fig. 8 represents a section on line 8—8 of Fig. 6.

The same reference characters indicate the 50 same or similar parts in all the views.

Referring to Figs. 1, 2, 3 and 4 of the drawings, 12 represents a body layer preferably of leather, and 13 represents a facing layer preferably of canvas cemented to one 55 side of the body layer. The facing layer

is molded prior to its attachment to the body layer, to form a loop-like rib or wale 14, which in the completed sole forms a stitch-engaging lip, suitable molding dies being employed to act on a narrow elongated portion of said layer and force said portion outwardly from one side of the plane of the layer. Said dies are formed to corrugate the sides of the lip by imparting thereto alternating recessed portions 14^a and bosses 14^b.

In the embodiment of the invention shown by Figs. 1 to 5 inclusive, both sides of the rib are thus corrugated, the bosses forming buttresses which prevent the lip from tipping sidewise in either direction. The lip is therefore enabled to stand up against pressure tending to crush or distort it.

In the embodiment shown by Figs. 6, 7 and 8, the lip 140 is provided with alternating recesses 140^a and 140^b at its inner side 75 only, its outer side being without corrugations.

The bosses are hollow, so that their outer surfaces are adapted to be forced inwardly by the inseam stitches engaged with the lip 80 by a welt sewing or stitching machine.

To prevent the toe portion of the facing layer and the curved toe portion of the lip from being displaced inwardly by the pressure of the toe wipers of a lasting machine 85 against the toe portion of the lip, I unite the facing and body layers by a curved line of stitches 17 extending beside the base of the lip and preferably at the outer side thereof, as shown by Figs. 1 and 2.

A coating 18 of shellac or other suitable material indicated by the shaded portion of Fig. 1 and the relatively heavy blank line in Fig. 2 is applied to the toe portions of the facing layer and lip to prevent the softening of the lip by vapor. It is now customary to place the inner sole and upper on a last, the toe portion of the upper being provided with an unlasted toe cap, and to insert the toe portions of the last and upper 100 into a casing containing hot vapor for the purpose of softening the toe cap before lasting the toe portion of the upper. The coating 18 is of a material which resists the softening action of the vapor, so that it prevents the softening of the toe portion of the lip.

Having described my invention, I claim:

1. An inner sole composed of a body layer and a facing layer having a molded hollow

inseam stitch-engaging lip, said lip being embossed to form corrugations laterally stiffening the lip.

2. An inner sole composed of a body layer and a facing layer having a molded hollow inseam stitch-engaging lip, said lip including alternating recessed portions and bosses whereby the lip is laterally stiffened.

3. An inner sole composed of a body layer and a facing layer having a molded hollow inseam stitch-engaging lip, the toe portion

of the facing layer and the toe portion of the lip being provided with a vapor-resisting coating to prevent softening of said portions by vapor employed to soften an associated portion of an upper. 15

In testimony whereof I have affixed my signature, in presence of two witnesses.

CONRAD B. MANSBACH.

Witnesses:

C. HAROLD PORTER,

JOHN T. GORDON.
